No 2648 —

C. Chinnock's Design for Clock Case Fronts.

Patented May 16. 1854 —

Fig. 1.

Fig. 2.

Fig. 3.

Des. 648

Charles Chinnock, Jr., of New York, N.Y.
Letters Patent, No. 648. Granted May 16, 1834

The schedule referred to in those Letters Patent, & making part of the same.

To all whom it may concern:

Be it known that I, Charles Chinnock, of the City, County, and State of New York, have invented or produced a new ornamental design for clock case fronts of Cast Metal: and I do hereby declare that the following is a full, clear, and exact description of the same, reference being had to the accompanying drawing forming part of this Specification, in which,

Fig. 1, is a front view of a clock case front of my design.

Fig. 2, is a side view of the same.

Fig. 3, is a vertical section of the same thro' the center.

The corresponding parts of the different Figures are indicated by the same letters of reference.

The front consists of a single plate, the general form of which is slightly convex.

The opening, for the clock face is surrounded by a light, narrow flat, moulding, α , which rises from the plate with a slight hollow sweep as shown at v, v , in Fig. 3.

An ornamental border surrounding the whole plate, is formed by slightly raised scroll tracery, $c, d, d, e, e, g, g, h, h, i$, of which the scroll, e , form the feet which support the front.

The whole plate is as nearly as possible of uniform thickness and is as light as is consistent with proper strength.

What I claim as my invention or production, and desire to secure by Letters Patent, is,

The design and configuration of the plate represented in the accompanying drawings and herein described, forming the front for a clock case.
